MERCHANDISE DISPLAY CABINET

Donald J. Guilford, 62 E. Victory Road, Henderson, Nev.

Filed Sept. 8, 1959, Ser. No. 57,481

Term of patent 14 years

(Cl. D80—11)

Fig. 1 is a front elevational view of merchandise display cabinet showing my new design;

Fig. 2 is a top plan view thereof;

Fig. 3 is a right side elevational view thereof, the left side being substantially the same as the right side shown;

Fig. 4 is a rear elevational view thereof;

Fig. 5 is a transverse sectional view thereof taken on line 5—5 of Fig. 1, the top of the inside being substantially the same as the bottom shown; and

Fig. 6 is a vertical sectional view thereof taken on line 6—6 of Fig. 1, the inside surfaces of the right side being reflective similar to the inside of the left side shown.

I claim:

The ornamental design for a merchandise display cabinet substantially as shown and described.
